UNITED STATES PATENT OFFICE.

JOHN I. MELTON, OF CINCINNATI, OHIO.

COMBINATION-TOOL.

No. 898,667.

Specification of Letters Patent. Patented Sept. 15, 1908.

Application filed February 4, 1907. Serial No. 355,581.

To all whom it may concern:

Be it known that I, JOHN I. MELTON, a citizen of the United States, residing at Cincinnati, in the county of Hamilton and State 5 of Ohio, have invented certain new and useful Improvements in Combination-Tools, of which the following is a specification.

My invention relates to improvements in combination tools. One of its objects is to 10 provide an improved form of combination tool which is readily adapted to be used for a variety of purposes.

Another object is to provide such a tool of a form adapted to be employed for the various 15 purposes as readily as though designed solely for the one purpose or use.

Another object is to provide a tool of simple form adapted to be produced by the process of casting or drop forging.

It further consists in certain details of form, combination and arrangement, all of which will be more fully set forth in the description of the accompanying drawings, in which:

25 Figure 1 is a side elevation of my improved tool. Fig. 2 is an end view of the same. Fig. 3 is a section through the same on line $v v$ of Fig. 1. Fig. 4 is a side elevation of the tool adapted for use as a hack saw. Figs. 5 30 and 6 are end views of the respective saw brackets or holding arms. Fig. 7 is a perspective view of one of the saw bars.

Referring to Fig. 1, A represents the shank or handle of the tool, which has formed integral therewith at one end a cross head A', which is adapted at one side a to serve as a wrench jaw, and at the opposite side a' to serve as a hammer. An undercut recess a^2 serves as a nail or tack puller. The opposite 40 end of the shank has a reduced portion a^3 , and terminates in a screw driver a^4 . A portion of one edge of the shank is provided with teeth a^5 . B represents a sliding or movable wrench jaw adapted to co-act with the jaw a . Jaw B has a rectangular recess b through which the shank A passes. C represents a pawl pivoted at c to jaw B and seated in a recess b' therein. Pawl C as shown in Fig. 1 is provided with a spring 45 handle c' which is adapted to be pressed against the shank A in grasping the tool, which firmly locks the jaw B to its adjusted position. Handle c' also serves as a convenient means for lifting the pawl and shifting the jaw B when desired. A spring c^2 serves to normally hold pawl C in engage-

ment with the shank A when the pawl is not being held in place by handle c' . In Fig. 4 I have shown a modification of the pawl C in which the handle c' is omitted and a finger c^3 60 is provided to release the pawl when it is desired to shift jaw B.

In Fig. 4 I have shown the tool adapted to be used as a hack saw. A saw holding arm or bracket D is slotted at d to span the shank 65 A, and clamped between the jaws A' B, small hooks or lugs d' assisting to retain it in place. A saw bar E having a rectangular shank e at its head e' , seats in one or other of rectangular recesses d^2 at opposite ends of the eye d^3 70 of bracket D, the bar E passing through the eye d^3 . F represents a saw bracket having a rectangular recess or eye f to seat on the reduced end a^3 of shank A. At the opposite end bracket F has an eye f' terminating at 75 opposite ends in rectangular recesses f^2 . Saw bar G passes through eye f' and has a spline g' by means of which it is slidably connected to a rectangular collar h^2 , which seats in one of the recesses f^2 . Bar G is provided with a 80 reduced threaded shank g , which is threaded into the saw handle H, by means of which the desired tension may be put upon the saw, the handle H turning against the collar h^2 . The saw I is attached to the saw bars by 85 means of hooks or pins $h' h''$ carried by the respective saw bars.

By reversing one or both of the saw brackets D F as indicated in dotted lines Fig. 4, saws of different length may be employed. 90 By giving bar E and collar h^2 a quarter turn the saw may be made to stand at right angles, which is desirable for certain work. Handle H may be adjusted to either bracket D or F as may be found most convenient for 95 the operator.

By inserting a pin through the holes r in bracket D, bracket D and jaw B may be shifted to any desired position away from jaw A' to accommodate shorter saws. 100

The tool herein shown and described is capable of considerable modification without departing from the principle of my invention.

Having described my invention, what I 105 claim is:

1. In an article of the character indicated a wrench having a shank, a stationary jaw and a movable jaw, a pair of arms supported laterally upon said shank, one of said arms 110 being supported between said jaws, and the other arm being supported upon a reduced

section of said shank at the opposite end from said jaws, said arms being adapted at their extremities to support a saw.

2. A wrench comprising a shank having 5 clamping jaws at one end and a reduced section at the opposite end of said shank, a pair of arms supported laterally upon said shank, one of said arms being supported by clamping between said jaws and the other arm supported by means of an eye upon said reduced section of the shank, and means at the outer extremities of said arms to support a saw blade.

3. A wrench comprising a shank having 15 clamping jaws at one end and a reduced section at the opposite end of said shank, a pair of curved arms supported laterally upon said shank and adapted to be reversed relative thereto so as to vary the distance between 20 the extremities of said arms, one of said arms being supported by clamping between said jaws and the other arm supported upon said

reduced section of the shank, and means at the extremities of said arms to support a saw blade.

4. A wrench comprising a polygonal shank having teeth upon one face, a stationary wrench jaw, a movable wrench jaw, a spring pawl to lock said movable jaw and a reduced polygonal section at the opposite end of said shank, a pair of arms supported laterally upon said shank, one of said arms being supported between said jaws by clamping, and the other arm supported by an eye upon said reduced section of the shank, the outer extremities of said arms being provided with means to support a saw blade.

In testimony whereof I have affixed my signature in presence of two witnesses.

JOHN I. MELTON.
